United States Patent Office.

JOHN H. GARNHART, OF ST. LOUIS, MISSOURI.

Design No. 3,943, dated March 29, 1870.

DESIGN FOR A TRADE-MARK.

The Schedule referred to in these Letters Patent and making part of the same

---

To all whom it may concern:

Be it known that I, JOHN H. GARNHART, of the city and county of St. Louis and State of Missouri, have invented and produced a new and original Design for a Trade-Mark, of which the following is a full, clear, and exact description, reference being had to the annexed photograph of same.

My design consists of a card or label having in the center the representation of a log cabin surrounded by trees, and in the foreground a woodman in the act of felling one of the trees, as seen in the illustration

annexed. Above the cabin are the words "Old Cabin Bitters," in letter-press, and around the whole is a border, as shown.

What I claim as my invention, and desire to secure by Letters Patent, is—

The design for a trade-mark, as described and shown.

J. H. GARNHART.
